UNITED STATES PATENT OFFICE.

GEORGE W. CHAMBERLIN, OF WORCESTER, MASSACHUSETTS, ASSIGNOR TO
EDWARD W. VAILL, OF SAME PLACE.

FOLDING CHAIR AND SETTEE.

SPECIFICATION forming part of Letters Patent No. 223,883, dated January 27, 1880.

Application filed May 12, 1879.

To all whom it may concern:

Be it known that I, GEORGE W. CHAMBERLIN, of Worcester, in the State of Massachusetts, have invented an Improvement in Folding Chairs and Settees, of which the following is a specification.

In this chair there are folding X-legs and folding arms. The back is suspended near the upper edge from the upper ends of the arms. The seat is hinged at the back to the top of the front legs, and such seat rests at its front edge upon the cross-rail between the upper ends of the back legs, and the bottom edge of the back rests upon the seat, and is united to the same by pins or cleats.

In the drawings, Figure 1 is a vertical section transversely to the seat and back. Fig. 2 is a front elevation, and Fig. 3 is a section of the chair or settee folded.

This improvement is especially adapted to settees; but by shortening the length of the seat and back portions and the connecting-rails the same is equally available for a chair.

The X-legs *a b* are united together at the central rail, *c*, and they are also connected by the bottom rails, *d d*, and seat-rails *e f*.

The rigid seat *g* is attached at the back, preferably to the rail *f* between the upper ends of the front legs, and said seat rests upon the front rail, *e*. The front stiffening-flange, *h*, prevents the X-legs spreading by the weight on the seat; or there may be hooks upon the under side of the seat for the same purpose. These hooks are shown in Fig. 1 by dotted lines.

The arm-pieces *k* are pivoted at their lower ends to the cross-rail *e*, and supported by the links *l* from the back rail, *f*, to the pivot *i*, and there may be rests or arm *o* upon the arm-pieces *k*. These arm-pieces *k* extend sufficiently above the seat and to the rear to suspend the back *m* from the pivots *n*.

The lower edge of the back rests upon the seat *g*, and it is prevented from moving backwardly by pins or dowels connecting such seat and back; or there may be a cleat at the back edge of the seat for the same purpose.

When the top edge of the back is lifted the dowels separate, the lower edge of the back can be swung forwardly, the front edge of the seat raised, and the X-legs will spread apart at the bottom, and the chair or settee will fold downwardly, the back lying upon the seat, as indicated in Fig. 3; and the parts will occupy but little space in transportation.

55

I claim as my invention—

The combination, in a folding chair or settee, of the folding X-legs, rail *e*, seat *g*, hinged at the back, the flange or hooks *h* at the front edge of the seat, the folding arm-pieces *k*, links *l*, and back *m*, suspended near its upper edge from the arms *k*, substantially as set forth.

Signed by me this 30th day of April, A. D. 1879.

GEORGE W. CHAMBERLIN.
